UNITED STATES PATENT OFFICE.

HORACE R. ALLEN, OF INDIANAPOLIS, INDIANA.

CHROMATIC PRINTING APPARATUS.

SPECIFICATION forming part of Letters Patent No. 322,147, dated July 14, 1885.

Application filed September 4, 1883. Renewed May 25, 1885. (No model.)

To all whom it may concern:

Be it known that I, HORACE R. ALLEN, a citizen of the United States, residing at Indianapolis, in the county of Marion and State of Indiana, have invented a new and useful Chromatic Printing Apparatus, of which the following is a specification.

The invention relates to chromatic printing devices; and it consists in the novelty of construction, arrangement, and adaptation of parts, as will be more fully hereinafter set forth, and specifically pointed out in the claims.

The object of the invention is to provide a device which shall automatically mark an advertisement or the like in an ink different in color from that used on the printing-roller. Various devices for similar purposes have before been devised. I employ the mechanism illustrated in the accompanying drawings, in

which—

Figure 1 is a vertical section of the entire machine of one form of construction; Fig. 2, a top view of the same machine as it appears when the electrotype plate or top of the machine is removed. Fig. 3 is a vertical section showing an inking-ribbon in connection with the lever and plunger.

Similar letters refer to similar parts throughout the several views.

In Fig. 1 A is the electroplate containing the electrotyped matter to be printed in the marked article. This plate, instead of being blocked on a solid wood or metal base, as is customary with electrotypes, is placed over and forms the lid of a hollow metallic box, S S, Fig. 1, and S S L L, Fig. 2, which serves as a reservoir for a colored ink.

The sides of the plate A rest firmly on the sides L L of the box, Fig. 2, and when necessary additional firmness may be given the plate by running supports up from the bottom of the box. Within this box a double lever, D D, Figs. 1 and 2, joined by the cross-arm I, Fig. 2, is adjusted, and works freely on the pivot E, Figs. 1 and 2.

The cross-arm I, connecting the two parts D D of the lever, is provided with two rigid pins, F F, Fig. 2, placed near the ends of the cross-arm. These pins give a bearing to the depressing-plunger G, which rests on and is supported by the pins. The plunger G is free to

move up and down, and to insure its moving in a firm and even manner its ends are grooved to receive the guides J J, which project from the sides of the box. The plunger G is made 55 to project above the surface of the type, and may be made rounding to guard against injuring the rollers, or it may be covered with a row of type.

On the opposite end of the lever from the 60 arm I is attached the marker C, Figs. 1 and 2. This marker is a strip of any form, and is allowed to stand above the lever D D just high enough to bring the upper edge against the paper when the plunger G is depressed to the 65 level of the type A.

H, Figs. 1 and 2, is a stiff spring, one end of which is fastened securely to the bottom of the box and the other allowed to bear against the cross-arm I on the short end of the lever 70 D, keeping the long end of the lever, with its attached marker, always against the bottom of the box, unless force enough is brought to bear, through the medium of the depressing device G and the pins F F, on the short end 75 of the lever to overcome the tension of the spring H.

Suitable openings are left in the lid or plate A to accommodate the working of the parts C and G.

This style of machine can only be used on printing-presses having a flat bed. Its practical operation is as follows: The printing device is placed in the form to be printed, and is locked up firmly like a common electrotype. 85 The form is then placed on the press, and before the press is started the hollow box or reservoir under the plate A, in the printing device, is filled with common fluid ink of any desired color, as carmine. The press is then 90 started, and to keep the ink in the reservoir from slopping the space below the lid may be filled with sponge. The device G should project above the surface of the type to such a distance that when it is forced down by the 95 platen of the press to the level of the type the marker C on the opposite end of the lever D will be raised to a level with the type.

The ink-rollers, owing to their yielding nature and to the stiffness of the spring H, do not 100 in passing over the form press the device G down far enough to raise the marker C to the

surface, but when the printed impression is made the force is sufficient to bring the device G down to a level with the type, thereby raising the marker C, which retains enough ink 5 on its upper edge to mark the paper.

In Fig. 3 I show the same arrangement of parts with an endless inking-ribbon, R. This ribbon winds upon one roller, P, and off another roller, O, or vice versa, and each roller has 10 a ratchet-face, the ratchets of one roller being arranged reversely to those of the other roller. A pivoted pawl, M, may be thrown at will so as to engage either roller, and the ribbon passes over the marker C, and along the bottom of 15 the reservoir, to insure that it will reach the ink.

It will be observed that the lever having the marker C on the longer arm insures that such plate shall come into forcible contact with 20 the paper as soon as the ordinary pressure is made upon the plunger G, the spring only acting to hold said marker out of contact at all other times, and also insures that the marker shall reach the ink in the reservoir.

25 What I claim as new, and desire to secure by Letters Patent, is—

1. In a printing device, the combination of a box, an electroplate secured thereto, a lever fulcrumed in such box, carrying a marker, and a plunger acting upon such lever, substantially 30 as set forth.

2. In combination with an ink-holding box or reservoir and an electroplate secured thereto above the surface of the ink, a lever fulcrumed in such box and carrying a marker, and a 35 plunger acting upon such lever to throw the marker against the paper being printed, as herein described.

3. In combination with an ink reservoir or box and attached electroplate, as described, a 40 lever pivoted in such reservoir or box and carrying a marker, a spring to hold the marker end of the lever to the ink, and a plunger acting upon such lever to overcome the action of the spring and throw the marker against the 45 paper being printed, as set forth.

HORACE R. ALLEN.
